UNITED STATES PATENT OFFICE.

CHARLES ALGERNON PARSONS, EBENEZER BENNETT, AND HARRY ROWE, OF
NEWCASTLE-UPON-TYNE, ENGLAND; SAID BENNETT AND ROWE ASSIGNEES
TO SAID PARSONS.

MOUNTING OF REFLECTORS.

1,309,542.

Specification of Letters Patent.

Patented July 8, 1919.

Application filed September 6, 1918. Serial No. 252,905.

To all whom it may concern:

Be it known that we, CHARLES ALGERNON PARSONS, K. C. B., EBENEZER BENNETT, and HARRY ROWE, all subjects of the King of Great Britain and Ireland, and all residing at Heaton Works, Newcastle-upon-Tyne, in the county of Northumberland, England, have invented certain new and useful Improvements in the Mountings of Reflectors, 10 of which the following is a specification.

The present invention relates to mounting reflectors and particularly to the mounting of reflectors for searchlights.

It has been the usual practice to mount 15 such reflectors upon a number of brass springs bolted to a steel ring, the ends of the springs being so shaped that they embrace the edge of the reflector. The steel ring has been provided with numerous slots or holes 20 through which the bolts pass so that when mounting the reflector the springs can be adjusted to exert as far as possible equal pressures in the direction perpendicular to the plane of the mirror. In practice, however, 25 it is found that the pressure is by no means equalized and the mirror is stressed and its accuracy of figure distorted so that an increase of divergence and irregularity of the beam results.

30 The object of the present invention is to obviate the necessity for great care in the setting of the springs, and further, to prevent the danger of distortion of the mirror arising from the distortion of the projector 35 ring from heat or other causes.

Reflecting mirrors of telescopes have been supported on systems of levers consisting of superimposed triangles giving 9, 27, 81, or more points of equal support, or on three 40 sector plates mounted on pivots at their center of pressure and bedded with felt or tallow against the back of the reflector.

According to the present invention, modifications of these principles of support are 45 adapted to the mounting of searchlight reflectors.

The invention consists in mounting the reflector on a number (3 or a multiple of 3) of supporting members symmetrically 50 placed around the mirror, each supporting member carrying clips embracing the edge of the mirror at equal intervals around its circumference.

The invention further consists in the improved mounting for reflectors hereinafter 55 described.

Referring to the accompanying drawings:—

Figure 1 is a front view,

Fig. 2 a part view of a mounting according to the invention;

Fig. 3 is a front view, and

Figs. 4 and 5 part sections of another form of mounting;

Fig. 6 is a front view,

Fig. 7 is a part section of a third modification;

Fig. 8 is a back view, and

Figs. 9 and 10 details of another form.

In carrying the invention into effect as 70 illustrated in Figs. 1 and 2, we provide three ring sectors *a* called primary sectors, of suitable cross-section, each surrounding somewhat less than one-third of the edge of the mirror. Each of these primary sectors 75 is pivoted at its center on a pivot *p* attached to the projector ring *d*. To the ends of each sector *a* are pivoted at their centers short sector or secondary sector levers *b*, and to each end of these secondary sectors is attached a suitable clip *c* which embraces the edge of the mirror *e* of the metal band *f* which surrounds the mirror. The lengths of the primary and secondary sectors are such that when placed in position the 12 85 clips are equally spaced around the mirror.

The pivots of the sectors are given a considerable amount of freedom, and it will be seen that the pressure exerted by the four 90 clips supported by each of the three primary levers must be equal both in the direction perpendicular to the plane of the mirror as well as in the radial direction.

Though twelve clips or supports are mentioned, tertiary levers may be pivoted at 95 their centers on the ends of the secondary sectors and clips attached to their ends, thus providing 24 supports, and in the case of small mirrors the clips may be attached to the ends of the primary levers, providing 6 100 supports.

In the form of the invention shown in Figs. 3 to 5, the primary sectors *a* are pivoted on pins *p* in the plane of the edge of the mirror, freedom of movement being assisted by spring washers *k*. The secondary

sectors *b* are pivoted loosely on pins *q* and carry at their ends the screw clip *r* which embraces the edge of the mirror.

In some cases where the projector is intended for use at high angles, additional support to the back of the mirror is provided as shown at Figs. 6 and 7. In this form of the invention, supporting brackets 1 are fixed to the reflector ring 2 and carry levers 3 mounted on pivots 4. The outer ends of the levers 3 carry the primary sectors *a* on pivots *p* while the inner ends carry pivots 5 for star shaped supports 6, each arm of the supports 6 carrying an asbestos or other suitable pad 7 which supports the back of the mirror. The star shaped supports are adjustable by means of the screw 8. The secondary sectors *b* carrying the clips *c* are mounted as before at the ends of the primary sectors *a*.

Further, instead of star shaped supports, plates of other form, or triangles, may be used, each extremity carrying a small plate similarly covered, the position of the fulcrums of the levers being arranged so as to give the desired distribution of pressure between the edge supports and the back supports so as to obviate flexure of the mirror.

In the form of the invention shown at Figs. 8, 9 and 10, the primary sectors *a* are mounted on pivots *p* fixed to the rear edge of the reflector ring *h*, and carry at their ends the pivots 11 of the secondary sectors *b*. The secondary sectors at their centers 35 are provided with rounded projections 12 to allow movement in planes passing through the pivots; long clips 13 to embrace the edge of the mirror are fixed to the ends of the secondary sectors. A stay 14 is fixed across the reflector ring *h* at the back of the mirror.

On a projector where a mirror ring cannot be applied, brackets carrying the sectors may be fixed to the projector back.

Though pivots have been described, ball

and socket or other means of flexure may be used, suitable means being provided to limit the motion in certain directions to secure the steadiness of the mounting.

It will be seen that it is not essential with this mounting that the springs should be carefully adjusted and no ordinary deformation or expansion by heat of the projector will cause distortion of the reflector.

Having now described our invention, what we claim as new and desire to secure by Letters Patent is:—

1. A reflector mounted on a number of pivoted supporting members symmetrically placed around the mirror, each supporting member carrying clips embracing the edge of the mirror and bearing on its front and rear surfaces at equal intervals around its circumference, substantially as described.

2. A reflector mounting comprising a number of primary members pivoted on fixed supports, each primary member having pivoted thereto secondary members carrying at their ends clips embracing the edge of the mirror, substantially as described.

3. In a mounting as claimed in claim 1, supports for the back consisting of pivoted plates or the like bearing at three points against the back of the mirror, substantially as described.

4. A reflector mounting comprising levers pivoted to the reflector ring or other fixed support carrying at their outer ends pivots for primary sectors which carry secondary sectors embracing the ends of the mirror, such levers carrying at their inner ends pivoted members provided with three supports bearing against the back of the mirror, substantially as described.

In testimony whereof we have signed our names to this specification.

CHARLES ALGERNON PARSONS.

EBENEZER BENNETT.

HARRY ROWE.
